UNITED STATES PATENT OFFICE

131,166

DESIGN FOR A VEHICLE BODY

William T. Rossell, University City, Mo., Francis H. Shepard, New Rochelle, N. Y., and Harry J. Bader, Troy, Ohio

Application March 4, 1941, Serial No. 99,340

Term of patent 7 years

To all whom it may concern:

Be it known that we, William T. Rossell, Francis H. Shepard, and Harry J. Bader, citizens of the United States of America, residing at University City, in the county of St. Louis and State of Missouri; New Rochelle, in the county of Westchester and State of New York; and Troy, in the county of Miami and State of Ohio, respectively, have invented a new original, and ornamental Design for a Vehicle Body, of which the following is a specification, reference being had to the accompanying drawing, forming a part thereof.

In the drawing:

Fig. 1 is a front elevational view of a vehicle body showing our new design;

Fig. 2 is a fragmentary side perspective view of the front portion of the vehicle body;

Fig. 3 is a perspective view of the vehicle body showing the front and one side of the vehicle body partly in dotted lines; and

Fig. 4 is a perspective view of the vehicle body showing the front and the other side of the vehicle body also partly in dotted lines.

The dominant feature of our design resides in the portion shown in full lines.

We claim:

The ornamental design for a vehicle body, substantially as shown and described.

WILLIAM T. ROSELL.
FRANCIS H. SHEPARD.
HARRY J. BADER.
